UNITED STATES PATENT OFFICE.

EMIL FOX, OF NEW YORK, N. Y., ASSIGNOR TO WM. MANNHEIM & CO., OF SAME PLACE.

DESIGN FOR A BOX-LOOP FOR HARNESS.

SPECIFICATION forming part of Design No. 20,718, dated **May 12, 1891.**

Application filed **March 20, 1891.** Serial No. 385,823. Term of patent 14 years.

To all whom it may concern:

Be it known that I, EMIL FOX, of the city, county, and State of New York, a citizen of the United States, have invented and produced 5 a new and original Design for Box-Loops for Harness, of which the following is a specification.

This invention relates to a design for box-loops for harness; and the design consists of 10 embossed and intertwining circles within an oblong frame.

The nature of my design is clearly shown in the accompanying drawing, to which reference is made.

15 A in the drawing represents a box-loop for harness, the face of which is ornamented by a series of embossed circles *a*, intertwined

with each other and arranged in an oblong embossed frame *b*.

Having thus described my invention, I claim 20 as new and desire to secure by Letters Patent—

A design for the face of a box-loop for harness, composed of a number of embossed and intertwining circles and an oblong embossed 25 inclosing frame, substantially as set forth.

In testimony that I claim the foregoing as my invention I have signed my name in presence of two subscribing witnesses.

EMIL FOX.
